UNITED STATES PATENT OFFICE

OSCAR L. LAWSON, OF LYNN, MASSACHUSETTS, ASSIGNOR TO UNITED SHOE MACHINERY CORPORATION, OF PATERSON, NEW JERSEY, A CORPORATION OF NEW JERSEY

SEWING MACHINE

Application filed January 5, 1926. Serial No. 79,453.

The present invention relates to sewing machines and more particularly to a presser foot lifting mechanism adapted for use in a lockstitch horn sewing machine.

5 The object of the invention is to provide a presser foot lifting mechanism of new and improved construction which will operate in an accurate and reliable manner to lift the presser foot a uniform distance during each 10 cycle of operations of the machine irrespective of the thickness of the work.

A further object of the invention is to provide a mechanism of this character in which the parts are so constructed and arranged as 15 to prevent all possibility of lost motion or slipping.

With these objects in view the invention consists of the devices, combinations and arrangement of parts hereinafter described and 20 claimed. While the invention is particularly adapted for use in a lockstitch horn sewing machine it is also capable of use in other types of sewing machines.

The several features of the present invention and the advantages attained thereby will be readily understood by those skilled in the art from the following description taken in connection with the accompanying drawings which illustrate the features of the invention 25 as embodied in a lockstitch horn sewing machine, so much only of the machine being indicated as is necessary to show the connection of the invention therewith.

In the drawings Figure 1 is a left elevation of the presser foot lifting mechanism, Fig. 2 is a front elevation of the same, Fig. 3 is a detailed rear elevation of part of the presser foot lifting mechanism including the bell crank lever and its cam, Fig. 4 is a detailed side elevation, and Fig. 5 is a detailed rear elevation of the wedge adjusting mechanism.

The lockstitch horn sewing machine therein illustrated includes a straight hook needle indicated at 6, a presser foot 8, a shuttle with its bracket 10, and a horn which serves as a work support as indicated at 12.

The needle is fast to the lower end of the needle bar 14 which is connected through link 16 with one end of the lever 18, the other

end being pivoted on the machine frame at 20. The lever and needle bar are actuated from the cam shaft 22 by a roll 24 mounted on the lever which engages a cam groove 26 in the cam disk 28.

55 The presser foot lifting mechanism, which embodies the subject-matter of this invention, comprises a lifting lever, pivoted directly in front of the presser foot bar on the machine frame, a block secured to the presser foot bar 60 and a cam-actuated bell crank lever to operate the lifting lever. A wedge inserted between the lifting lever and the block provides a means automatically to adjust the lifting mechanism to raise the presser foot a uniform distance irrespective of the thickness of the work. A bell crank lever is mounted on the presser foot bar with its lower arm connected to the wedge and its horizontal arm arranged to engage an abutment on the machine frame. During the downward stroke 65 of the presser foot the lever is turned about its pivot to withdraw the wedge a greater or less distance depending on the fall of the presser foot. During the lifting operation 70 the wedge thus positioned with relation to the thickness of the work is held in adjustment by means of a pinch dog mounted on the rear end of the lifting lever. The lifting movement of the cam-actuated bell crank 75 lever first causes the pinch dog to clamp the wedge and then turns the lifting lever about its pivot to raise the presser foot.

80 Describing this presser foot lifting mechanism somewhat more specifically with reference to the drawings, the presser foot bar 30 has fastened thereto a block 32 which has on its under side a groove 34 adapted to receive the upper edge of a wedge 36. A lifting lever 38 mounted on the machine frame at 85 40 directly in front of the presser foot bar has a corresponding groove 42 for the lower edge of the wedge. To hold the wedge in position during the lifting operation a pinch dog 44 is mounted on the rear end of the 90 lifting lever. The wedge is adjusted in accordance with the thickness of the work to allow the lifting lever always to raise the presser foot a uniform distance by means of a bell crank lever 46 pivoted on the presser 95

foot bar at 48. On the lower arm of this lever is a pin 50 which runs in a vertical slot 52 formed in the wedge. The horizontal arm carries a pin 54 which projects over a ledge or abutment 56 adjustably mounted on the machine frame by means of screws 57 projecting through vertical slots 58 in the frame. A spring 59 acting on the pin tends to force the horizontal arm of the lever downwardly. 5
10 As the presser foot falls, the lever is turned about its pivot by the engagement of the pin with the abutment to slide the wedge to the right. During the upward stroke of the presser foot, the wedge is held in position by 15 the pinch dog and the pin 54 is lifted off its abutment against the pressure of the spring 59. A set screw 62 is provided to adjust the position of the ledge or abutment and thus determine the distance the presser foot is to 20 be raised above the work. A bell crank lever 64 pivoted at 66 on the machine frame carries on its vertical arm a roll 68 adapted to run on the cam surface 70. The other arm is adapted to engage the pinch dog pivoted on 25 the lifting lever. The lever 64 engages the pinch dog, first locking the wedge and then turning the lifting lever about its pivot to raise the presser foot. In order to permit an adjustment of the effective throw of the bell 30 crank lever in its lifting movement the two arms are pivoted independently at 66 and are held in the desired relation to each other by means of set screws 72.

The nature and object of the invention having been indicated and a machine embodying the several features of the invention having been described, what is claimed is:

1. A sewing machine having, in combination, a work support, a presser foot, a presser foot bar, an abutment on the bar, a lifting member, a wedge interposed between the lifting member and the abutment, means for actuating the lifting member to lift the presser foot, and means for positioning the wedge with relation to the lifting member in accordance with the thickness of the work to raise the presser foot a uniform distance from the work to permit the feeding of the work. 40

2. A sewing machine having, in combination, a work support, a presser foot, a presser foot bar, a lifting member, an abutment on the presser foot bar, a wedge, a bell crank lever for positioning the wedge pivoted on the presser foot bar and having one end connected with the wedge, and an abutment on the machine frame to engage the other end of the bell crank. 50

3. A sewing machine having, in combination, a work support, a presser foot, a presser foot bar, a block fast to the bar, a lifting member, an adjustable wedge carried on the lifting member and arranged to come in contact with the block, and a bell crank lever pivoted on the presser foot bar and having

at one end a pin and slot connection with the wedge, and an abutment on the machine frame to engage the other end of the bell crank. 55

4. A sewing machine having, in combination, a work support, a presser foot, a presser foot bar, means comprising an adjustable wedge and a lifting member to raise the presser foot a uniform distance irrespective of the thickness of the work, means for positioning the wedge in accordance with the thickness of the work and a pinch dog to lock the wedge in position during the lifting operation. 70

5. A sewing machine having, in combination, a work support, a presser foot, a presser foot bar, an abutment on the presser foot bar, a lifting lever, an adjustable wedge supported on the lifting lever and arranged to come in contact with the abutment, a pinch dog pivoted on the lifting lever to lock the wedge in position, and means operating on the pinch dog to lock the wedge in position and thereafter actuate the lifting lever to raise the presser foot. 75

6. A sewing machine having, in combination, a work support, a presser foot, a presser foot bar, a block fixed to the bar, a lifting lever, a wedge arranged to cooperate with the lifting lever and the block to lift the presser foot, means for positioning the wedge to raise the presser foot a uniform distance regardless of the thickness of the work, a pinch dog to lock the wedge in position during the lifting operation, and means to operate the pinch dog to lock the wedge and thereafter actuate the lifting lever to raise the presser foot. 80

7. A sewing machine having, in combination, a work support, a presser foot, a presser foot bar, means comprising an adjustable wedge and a lifting member to raise the presser foot a uniform distance irrespective of the thickness of the work, a pinch dog to lock the wedge in position during the lifting operation, a cam, and a lever actuated by the cam to operate the pinch dog to clamp the wedge in position and thereafter to actuate the lifting member to raise the presser foot. 85

8. A sewing machine having, in combination, a work support, a presser foot, a presser foot bar, a block fixed to the bar, a lifting lever, an adjustable wedge supported on the lifting lever and arranged to come in contact with the block, a pinch dog pivoted on the lifting lever to lock the wedge in position, a cam and a bell crank lever actuated by the cam to operate the pinch dog to clamp the wedge in position and thereafter to actuate the lifting member to raise the presser foot. 90

In testimony whereof I have signed my name to this specification.

OSCAR L. LAWSON.
